UNITED STATES PATENT OFFICE.

JOHN F. WAIDELICH, OF JACKSON, AND THOMAS F. WHELAN, OF HOLLWAND,
MICHIGAN.

WEAR PLATE.

Specification of Letters Patent. Patented Aug. 22, 1922.

1,426,795.

Application filed January 23, 1920. Serial No. 353,508.

To all whom it may concern:

Be it known that we, JOHN F. WAIDELICH and THOMAS F. WHELAN, both citizens of the United States of America, residing at 5 Jackson and Hollwand, respectively, in the counties of Jackson and Ottawa, respectively, and State of Michigan, have invented certain new and useful Improvements in Wear Plates, of which the following is 10 a specification, reference being had therein to the accompanying drawings.

The invention relates to metallic wear plates for insertion in the soles of shoes, and the invention consists in the novel construction more particularly designed for use 15 as a toe plate, as hereinafter set forth.

In the drawings:

Figure 1 is a plan view of the blank of which the wear plate is formed;

20 Figure 2 is a central section through the dies used in forming the plate;

Figure 3 is a perspective view of the formed plate; and

25 Figure 4 is a section through the sole of a shoe into which the plate is inserted.

Our improved construction is formed from pressed sheet metal, the original blanks being preferably of rectangular form so as to permit of cutting without waste of 30 stock. These rectangular blanks A are pressed through a tapering die member B by a punch member C, the proportion of the parts being such that the blank is cupped and the corner portions turned upward.

35 The punch C has a flaring portion D for squeezing the prongs E formed by the corners of the blank, so as to both elongate and thin the same. Thus the completely formed article is provided with four prongs 40 E having sharpened ends, while the central portion of the blank is round in plan view and has rounded edges forming an annular flange F merging into the prongs E.

With the construction as described when 45 the prongs are driven into the sole of a shoe, the sharp edges will cut the latter and

will then be diverted laterally so as to form a clinch or locking connection, as indicated at G. The annular flange F will also be imbedded in the leather, leaving the round central portion substantially flush with the lower face of the sole. As all of the edge is rounded, there will be nothing to scratch or mar a floor and by reason of the lateral deflection or clinching of the prongs the 55 plate can not become accidentally detached.

What we claim as our invention is:

1. A wear plate for shoe soles, comprising a pressed sheet metal member formed from a rectangular blank and having a 60 rounded body portion with an inwardly extending annular flange surrounding the same and the corner portions of the blank forming slightly diverging prongs, the metal thereof being squeezed to thin the 65 same and form sharp edges for driving into the leather.

2. A wear plate for shoe soles, comprising a pressed rectangular sheet metal plate having a plurality of slightly diverging 70 sharpened prongs and a rounded body portion forming the wearing surface of the plate.

3. A wear plate for shoe soles, comprising a pressed sheet metal member formed 75 from a flat rectangular blank having an outwardly extending annular flange and the corner portions of the blank forming tapered prongs, the metal thereof being pressed to thin the same and form sharpened edges 80 for piercing the leather.

4. A wear plate for shoe soles, comprising a pressed sheet metal member formed from a rectangular blank having tapered 85 slightly diverging prongs, the metal of said prongs being thinned to elongate and sharpen the edges thereof.

In testimony whereof we affix our signatures.

JOHN F. WAIDELICH.
THOMAS F. WHELAN.
